UNITED STATES PATENT OFFICE.

JOHN JIRETZ, SR., OF TAMPA, FLORIDA.

DISHWASHER.

Application filed February 15, 1927. Serial No. 168,403.

This invention relates to a dish washer, and particularly to a construction including a tank provided with a cradle to carry the articles to be washed which are reciprocated 5 through the liquid within the tank.

It is particularly desirable in this art to provide a mounting for the cradle permitting its free reciprocation and an operating handle therefor which is adapted to be disposed 10 substantially within the tank when the washer is not in use. It is also important to so construct the tank that the discharge or waste therefrom may be controlled and any food particles or other matter caught and re- 15 moved before the discharge and also to construct the waste valve or plug so that the same will operate to maintain the necessary liquid level within the tank for the most efficient washing operation.

20 The invention therefore has for an object to provide the tank with a swinging cradle having mounted upon its hanger a sliding handle or operating lever adapted to be withdrawn from the tank when in position for operation and to be replaced therein at other times.

25 A further object of the invention is to provide an improved form of tank having a waste opening in connection with a tubular plug controlling said opening and open at its upper end to establish a proper water level relative to the cradle within the tank.

30 Another object of the invention is to provide an improved construction of a cradle comprising a frame of angle iron supported upon a yoke hanger and carrying guide strips outwardly deflected in opposite directions so as to facilitate the introduction and removal 35 of a basket carrying the articles to be washed.

40 Other and further objects and advantages of the invention will be hereinafter set forth and the novel features thereof defined by the appended claims.

In the accompanying drawings:—

45 Figure 1 is a section on the line 1—1 of Figure 2;

Figure 2 is a central vertical section at a right angle to Figure 1;

Figure 3 is a top plan;

50 Figure 4 is an enlarged elevation of the handle connection;

Figure 5 is a section on the line 5—5 of Figure 4; and

55 Figure 6 is a detail section of the waste plug.

Like reference characters designate corre-

sponding parts throughout the several figures of the drawing.

While the invention is shown and described in connection with a dish washing machine, 60 it is capable of other applications and the form or size of the tank may be varied at will. As shown in Figures 1 and 2, the tank 10 is provided with a longitudinally curved bottom 11 which is substantially concentric to 65 the arc of travel of the cradle 12 supported within the tank. This tank may be supported by any desired means such as the angle standards 13 at its corners, and is provided at its top with a partial cover 14 to prevent splashing 70 of the water at the opposite ends and a back board 15. At the central portion of the rear of the tank a depending well 16 is formed from which a discharge or waste pipe 17 extends. 75

The cradle may be suspended in any desired manner but preferably by means of a yoke hanger having the horizontal portion 18 upon which the cradle 12 rests and the vertical arms 19 formed at their upper ends 80 with pivots 20 operating in bearings 21 upon the cover portion 14 of the tank. This hanger may be formed of a rod of any desired cross section and is here shown as circular so as to receive the sleeve 22 carried by a face of the 85 handle bar or lever 23 provided at its free end with a handle 24. This sleeve is preferably formed with a friction fit upon the rod so as to retain it in its elevated position and a recess or seat 22^a to engage a pivot 20 when 90 raised to retain the handle against free rotation in the operation of the machine. Such a construction permits the handle to be inserted in the machine when not in use so as to be out of the way and permit the free introduction of the articles into the cradle. 95

The cradle is specifically formed of an angle iron frame 25 which rests upon the bar 18 of the hanger and is held and braced thereon by diagonally disposed braces 26 extending 100 from the ends of the frame and connected to the vertical portion 19 of the hanger. The cradle frame also carries the guide strips 27 which are outwardly deflected at their opposite ends 28 so as to guide into position 105 the wire or other form of basket 29 in which the dishes or articles to be washed are disposed. For the purpose of conveniently handling this basket it is formed with handles 30 at its opposite sides. 110

Under many conditions it is desirable to provide means for heating the water within

the tank and maintaining the same at a proper temperature for most efficient results and for this purpose a gas or other form of burner 31 may be disposed beneath the tank 5 and supported at one end by a bracket 32 from the well 16 and at its opposite end from the tank.

For the purpose of controlling the waste opening 17 a tubular overflow valve 33 is 10 provided and preferably disposed in a chamber 34 at the rear of the tank which communicates with a body of liquid therein through the well 16 which is provided with a removable reticulated basket 35 in order to retain 15 any solid material in the liquid. This tubular plug fits at its lower end in a seat 36 and is open throughout its length so as to establish the desired water level within the tank as it permits an overflow of the water there- 20 in when it reaches such elevation. The plug is guided in its vertical movement by the loops 37 formed at the ends of wall 37^a and provided at its upper end with a flexible connection 38 having a bail 39 engaging the tube 25 and adapted at its upper end to be engaged with either of a plurality of hooks 40 upon the back 15. As shown in Figure 2, when the plug is seated to close the waste opening the connection 38 is slack, and when the plug 30 is open it is sustained by this connection upon the upper hook 40.

The operation of the invention will be apparent from the foregoing description from which it will be seen that the construction 35 of tank provides means for securing an efficient washing action by the movement longitudinally therein of the liquid and basket while the cover of the tank prevents splashing and the drain well and plug provide

means for maintaining the desired water level 40 and emptying the tank when the water there- in is to be changed. Since it is most convenient to introduce the basket into the cradle from the front of the tank the collapsible 45 mounting of the handle is found an efficient element in operation while the tubular form of the waste plug combines in a single member means for control of the outlet and the water level.

While the specific details of construction 50 have been shown and described, the invention is not confined thereto as changes and alterations may be made without departing from the spirit thereof as defined by the ap- 55 pended claims.

Having thus described my invention, what I claim as new and desire to secure by Letters Patent is:—

1. In a dish washer, a tank, a hanger having vertical arms pivoted at the upper portion 60 of the tank, a cradle carried by the hanger, and a handle slidingly mounted upon one of said arms for adjustment relative to the cradle.

2. In a dish washer, a tank, a hanger having vertical arms pivoted at the upper portion of the tank, a cradle carried by the hanger, and a handle lever having a sleeve slidingly embracing one of said vertical arms. 65

3. In a dish washer, a tank, a hanger having vertical arms pivoted at the upper portion of the tank, a cradle carried by the hanger, a handle lever having a sleeve thereon slidably engaging one of the vertical arms, and means for retaining said sleeve against rotation upon the hanger. 70

In testimony whereof I affix my signature.
JOHN JIRETZ, Sr. 75
